NECKLACE OR SIMILAR ARTICLE

André Fleuridas, Westport, Conn., assignor to Mazer Bros., Inc., a corporation of New York

Application March 1, 1950, Serial No. 8,233

Term of patent 3½ years

(Cl. D45—16)

To all whom it may concern:

Be it known that I, André Fleuridas, a citizen of the United States and residing at Westport, in the county of Fairfield and State of Connecticut, have invented a new, original, and ornamental Design for a Necklace or Similar Article, of which the following is a specification, reference being had to the accompanying drawing, forming part thereof, and in which

Fig. 1 is a plan view of the necklace or similar article, showing my new design,

Fig. 2 is a side elevation thereof,

Fig. 3 is a plan view on an enlarged scale of a fragmentary portion of the necklace or similar article,

Fig. 4 is a side elevational view of the enlarged fragmentary portion shown in Fig. 3, and

Fig. 5 is a bottom plan view of the enlarged fragmentary portion shown in Fig. 3.

The dominant feature of my design resides in the elements disclosed in full lines, said elements being repeated throughout the length of the necklace as indicated by the broken line illustration.

I claim:

The ornamental design for a necklace or similar article, substantially as shown and described.

ANDRÉ FLEURIDAS.
